UNITED STATES PATENT OFFICE.

WILLIAM M. WILKIN, OF MOBILE, ALABAMA.

GANG-SAW MILL.

SPECIFICATION forming part of Letters Patent No. 730,063, dated June 2, 1903.

Application filed May 6, 1902. Serial No. 106,152. (No model.)

To all whom it may concern:

Be it known that I, WILLIAM M. WILKIN, a citizen of the United States, residing at Mobile, in the county of Mobile and State of Alabama, have invented certain new and useful Improvements in Gang-Saw Mills; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

15 My invention relates to improvements in gang-saw mills, and has for its object the overcoming of defects in the construction and operation of gang-saw mills as now made and improvements in the construction thereof by 20 means whereof I have greatly increased the capacity and improved the efficiency of the mill without materially increasing its weight and the cost of its construction.

The features of my improvements consist 25 substantially of the following, viz:

First. In constructing a gang-saw sash wide enough to saw two logs or cants at once and with a central support between the upper and lower girths of the sash, whereby I am enabled 30 to use a wide sash of but little more weight than that of an ordinary narrow sash, and on this support I provide a series of cutters or choppers adapted to cut away any projecting parts on the logs or cants passing there- 35 through, so as to prevent their contacting with said central support.

Second. In the operation of balanced gangs it is usual to provide a crank-shaft having U-shaped cranks in opposite directions, a pit- 40 man leading from one crank to the lower girth of the saw-sash, and a pitman leading from the opposite crank to a counterbalance-weight. This construction necessitates a heavy shaft, as the wrist-pins of the cranks are necessarily 45 a considerable distance apart longitudinally, and the strain of the work on the shaft necessarily causes it to vibrate, so that difficulty is frequently experienced in maintaining its bearings in proper condition, and when four 50 cranks and pitmen are used, as is necessary with wide saw-sashes, as in this case, this difficulty is greatly increased. In my con-

struction I have reduced these difficulties to a minimum by utilizing eccentrics instead of cranks, which eccentrics are secured close together on the shaft and, preferably, are made integral. By this means I am enabled to bring the lines of travel of the sash and weight pitmen close together, thereby reducing the vibration of the shaft to a minimum amount, 60 which enables me to use a comparatively small shaft, the bearings of which are easily kept in order.

Third. In the construction of the press-roll-operating mechanism of gang-saw mills screw 65 mechanism is ordinarily used; but it has been found desirable to operate them by means of steam or compressed-air cylinders; but as they have heretofore been constructed the cylinders were placed on the top of the mill-frame and connected directly to the press-roll 70 yoke. This construction not only greatly increased the weight of the structure, but so largely increased the height and weight of the top thereof that the vibration thereof, 75 caused by the rapidly-moving sash, has been uniformly so destructive to the structure, and as the pistons of the cylinders were connected with the center of the press-roll yoke the yoke would tilt and bind in its guides, so as 80 not to operate satisfactorily, which difficulties have prevented its use to any extent, though a rapid means of handling the press-rolls is greatly desired. I have overcome these difficulties by placing the cylinders near the base 85 on side of the lower part of the gang-saw frame and connected their pistons with arms on rock-shafts, and from other arms on said rock-shafts links extend to the ends of the press-roll yoke, to which they are detachably 90 connected, so that they can be disconnected and the press-roll mechanism swung back out of the way, so as to permit ready access to the sash. The arms on the rock-shaft, from which the links extend to the ends of the 95 press-roll yoke, I preferably make adjustable in length, so that if more pressure on the press-rolls is at any time desired the adjustable rock-shaft arms can be shortened and increased pressure thereby transmitted to the 100 press-rolls.

Fourth. Gang-saw mills are largely used for resawing cants or fitches which have been previously squared on two or more of their

sides, which cants or flitches are placed on the saw-carriage with one of the square faces thereof in contact with guides at the sides of the carriage. Heretofore it has been found difficult, if not impossible, to keep the cants or flitches constantly in contact with these carriage-guides, and as a result thereof the outside cut from the cant or flitch is nearly always of unequal thickness at its ends, and therefore not marketable lumber, and to overcome this difficulty I provide the carriage with a pair of diagonal or cut rolls, having teeth adapted to engage the under surface of the cant, which rolls are mounted on movable bearings, by means whereof the rolls can be raised into contact with the cant or flitch or lowered away therefrom at the will of the operator. These diagonal or cut rolls operate as the cants or flitches move over them to constantly carry the cant or flitch toward and against the saw-carriage guides, so that as the cant or flitch passes the saws the outer face thereof is constantly the same distance beyond the outside saw, so that the outside board cut off thereby will be of equal thickness throughout its entire length.

These and other features of my invention are hereinafter fully set forth and explained, and illustrated in the accompanying drawings, in which—

Figure 1 is a top or plan view of my improved gang-saw mill. Fig. 2 is a side view in elevation of the same. Fig. 3 is a front view in elevation of the same with the feed-rolls and base partly in section. Fig. 4 is a vertical section of the frame, sash, and mechanism on the line $x-x$ in Fig. 3 looking in the direction of the arrow. Fig. 5 is an enlarged view in elevation of the side of the saw-carriage, illustrating the operation of the diagonal or cut roll mechanism thereof.

In the drawings illustrating my invention, A A' are the sides, and B B' the base and top, of the frame of my improved gang-saw mill. In the upper part of this frame I mount a saw-sash C, which operates in the usual vertical guides a on the sides of the frame. This sash C, I make with a central brace or support D, which is firmly secured between the upper and lower girths C' C² of the sash C, so as to firmly support the central part thereof against the strain of the saws c. Upon this central brace or stile D, I secure cutters or choppers d, which are adapted to cut or chop away any portions of logs or cants which would contact with the support or brace D. For operating this saw-sash I mount a driving-shaft E on the base B of the frame, having the usual driving-pulley E' on one end and a friction-pulley E² on the other for driving the feed mechanism of the gang. On the central part of the shaft E in lieu of the ordinary U-shaped cranks I secure double eccentrics e e', the eccentrics e' being preferably much smaller than the eccentrics e. These eccentrics are secured to the shaft close together, with the throws thereof oppo-

site each other, and are preferably made integral with each other. From the eccentrics e pitmen F extend to the lower girth C² of the sash C, and from the eccentrics e' pitmen F' extend downward and connect with counterweights G, which swing upon a shaft G', mounted in bearings g g at one side of the base B of the frame, as clearly illustrated in Figs. 2, 3, and 4. It will be observed that by means of this construction I am enabled to get the lines of strain upon the eccentrics e and e' close together, while in the usual U-shaped-crank construction they are necessarily separated by the thickness of the arms of the cranks, and by this means I reduce the vibration of the shaft E, caused by the strain of the sash C and the counterweights G thereon, to a minimum and am enabled therefore to safely use a much smaller driving-shaft than is safe with the U-shaped-crank construction. Again, I preferably make the eccentrics e' approximately one-half the diameter of the eccentrics e and proportionately increase the weight of the counterweights G, which modification of the structure tends to greatly reduce the strain and vibration of the driving-shaft E and at the same time reduces the length of the parts projecting below the base of the frame, while in nowise interfering with the successful operation of the counterbalance-weights in counterbalancing the sash C.

The feed-roll mechanism of my improved structure is generally of the usual construction, it consisting of a vertical shaft I, provided with a friction-roll I', adapted to contact with the face of the friction-disk E². The shaft I is mounted at its lower end in a bearing i, which is adapted to be moved toward and away from the friction-disk E² when desired, and at its upper end in a sleeve i', mounted in a bearing i², through which the shaft I is adapted to be moved vertically and with which it is connected by a spline and groove i³, and upon the sleeve i' there is a bevel-pinion J, which intermeshes with a bevel-gear-feed-roll-driving wheel J', the shaft of which is provided with the usual pinion J², intermeshing with the gear-wheels K on the ends of the feed-rolls K'. For moving the shaft I up and down to vary the speed of the feed mechanism I secure a grooved collar I² to the shaft I, and extending from and pivoted to the side A of the frame there is an arm L, the end of which is bifurcated and fits the groove in the collar I², and through this arm L there is an adjusting-screw L, with a hand-wheel l thereon, by means whereof the outer end of the arm L and the shaft I can be raised and lowered as desired. The shaft I is also provided with a hand-wheel I³ for operating the same by hand when desired.

The press-roll yokes M are mounted upon removable vertical pins m m, which pass through supports a' a' on the side A' A of the frame, and the press-roll yoke M is adapted to slide up and down thereon or be swung

around horizontally on one of them when the other has been removed, as illustrated by dotted lines in Fig. 1. The press-rolls M' M' are mounted in this yoke M in the usual manner.

To one of the side frames of the mill, adjacent to or upon the base B of the frame, I secure cylinders N N, (see Figs. 3 and 4,) provided with fluid-actuated pistons and piston-rods N' and with the usual valve mechanism 10 n and supply-pipes n' leading thereto. To the piston-rods N', I pivot links n², which extend to arms O, secured to rock-shafts O', mounted in the side frames A A'. In sleeves P, secured to each end of the rock-shaft O', 15 there are telescoping arms p, from which links p' extend to each end of and are removably pivoted upon studs at the ends of the press-roll yokes M, so that the press-roll yoke M and the press-rolls M' M' can be moved up 20 and down thereby; but when it is desirable to detach the links p' from the press-roll yoke M it can readily be done by removing the loose pins m', after which the links p' can be detached from the press-roll yoke M. For 25 moving the arms p in the sleeves P on the rock-shaft O', mounted in the sides A A' of the frame, I provide transverse shafts Q, mounted in the sides A A' of the frame, and from arms Q' thereon links q extend to the links 30 p', so that the rocking of the shaft Q by means of the lever Q² at the side A of the frame operates to shorten or lengthen the arms p and correspondingly increase or diminish the power exerted by the cylinders N 35 upon the press-roll yokes M. While I have thus shown and described the arms p on the rock-shaft O' as adjustable and prefer a construction of this character, yet I can secure such arms directly to the rock-shafts O' without 40 providing for any adjustment of the length thereof and obtain excellent results. Therefore I do not confine myself to the peculiar construction of rock-shaft arms shown and described.

45 In constructing the saw-carriage of this mill I make it with the usual log or cant supporting rolls R, mounted in supports R' in the usual manner, and provide the carriage with the usual guides r at each side thereof; but 50 between the supporting rolls R, I mount on pivoted bearings at one end thereof yokes S diagonally to the guides r, as clearly shown in Fig. 1. In these yokes S, I mount spiked rolls S'. Across the carriage I mount a trans- 55 verse shaft T, provided with cams t t, upon which the free ends of the yokes S rest, which operates, when the shaft T is rotated, to raise and lower the rolls S', as is clearly illustrated in Fig. 5. At one side of the carriage the 60 shaft T is provided with an operating-lever T', by means whereof the shaft T can be rotated as desired.

I have thus described the several parts of the mechanism and their functions so fully 65 that it is believed further reference thereto is unnecessary. It is manifest, however, that many features of the invention herein shown

and described may be modified in their construction without departing from the spirit of my invention. Therefore I do not desire to 70 limit myself to the exact construction and arrangement of parts of my structure herein shown and described.

Having thus shown and described a convenient construction of mechanism which will 75 enable others skilled in the art to which it appertains to utilize my invention, what I claim as new, and desire to secure by Letters Patent of the United States, is—

1. The combination in a gang-saw mill, of 80 a frame, a saw-sash mounted on guides therein, a driving-shaft mounted in the base of the frame, sash and counterweight eccentrics secured upon said shaft in contact with each other so as to operate in opposition to each 85 other with a minimum vibration of the shaft, a pitman connecting the sash-eccentric with the sash, and a pitman extending downward from the counterweight-eccentric to and connecting with a counterweight, substantially 90 as and for the purpose set forth.

2. The combination in a gang-saw mill, of 95 a frame, a sash mounted therein, a driving-shaft mounted in the base of the frame, counterweights below said shaft and secured upon arms pivoted to the base of the frame, differential sash and counterweight eccentrics on 100 said shaft immediately adjacent to each other and operating in opposition, a pitman extending from the sash-eccentric to the saw-sash, and a pitman extending from the counterweight-eccentric to the counterweight, substantially as and for the purpose set forth.

3. The combination in a gang-saw mill, of 105 a frame, a sash mounted therein, a driving-shaft mounted in the base of the frame operating said sash, feed-roll mechanism operated by said driving-shaft, pressure-roll yokes carrying pressure-rolls mounted on said frame, a cylinder mounted near the base of said 110 frame, a fluid-actuated piston in said cylinder, an arm on a rock-shaft in said frame, connected with said piston-rod, adjustable arms on each end of said rock-shaft, and links connecting the same with said pressure-roll 115 yokes, substantially as and for the purpose set forth.

4. The combination with a gang-saw mill of a feedway comprising substantially log or cant carrying rolls, guides at the sides of the 120 feedway, vertically-movable roll-supports in said feedway, rolls diagonally mounted in said vertically-movable roll-supports and mechanism for raising and lowering said roll-supports so as to bring the rolls carried thereby 125 into or out of contact with logs or cants passing along said feedway and through the mill, substantially as and for the purpose set forth.

5. The combination with a gang-saw mill of a feedway comprising substantially log or 130 cant carrying rolls, guides at the sides of the feedway, roll-supports pivoted at one end and vertically movable at the other, diagonal cutting-rolls mounted in said supports, and

means for raising and lowering the free ends of said roll-supports, substantially as and for the purpose set forth.

6. The combination with a gang-saw mill
5 of a feedway comprising substantially log or
cant carrying rolls, guides at the sides of the
feedway, roll-supporting yokes pivoted at one
of their ends in fixed bearings and having their
other ends vertically movable, spiked dia-
10 gonal or cutting rolls mounted in said yokes,

and cam-and-lever mechanism for raising and
lowering the free ends of said yokes, sub-
stantially as and for the purpose set forth.

In testimony whereof I affix my signature
in presence of two witnesses.

WILLIAM M. WILKIN.
